UNITED STATES PATENT OFFICE.

JOHN J. BROWN, OF HOLLAND, MICHIGAN.

WASHBENCH.

Application filed June 29, 1925. Serial No. 40,280.

To all whom it may concern:

Be it known that I, JOHN J. BROWN, a citizen of the United States, residing at Holland, county of Ottawa, State of Michigan, have invented certain new and useful improvements in Washbenches, of which the following is a specification.

This invention relates to improvements in wash benches.

10 The main objects of this invention are to provide an improved wash bench which is well adapted for use in connection with washing machines, the bench being capable of modification in its arrangement of parts 15 so that it is adapted for supporting tubs in proper relations to the machine and wringer.

A further object is to provide a wash bench having these advantages which may be compactly collapsed for storage or transportation.

Objects pertaining to details and economies of my invention will definitely appear from the detailed description to follow.

I accomplish the objects of my invention 25 by the devices and means described in the following specification. The invention is clearly defined and pointed out in the claims.

A structure embodying the features of my invention is clearly illustrated in the accompanying drawing forming a part of this 30 application, in which:

Fig. I is a perspective view of a wash bench embodying the features of my invention with the main and auxiliary benches adjusted to one of its positions.

Fig. II is a side view of the bench collapsed.

Fig. III is a fragmentary section on a line corresponding to line 3—3 of Fig. I.

40 Fig. IV is a fragmentary view partially in section on a line corresponding to line 4—4 of Fig. I.

In the drawing the sectional views are taken looking in the direction of the little 45 arrows at the ends of the section lines and similar numerals of reference indicate similar parts in all of the views.

Referring to the drawing, my improved bench comprises a main bench member designated generally by the numeral 1 and an auxiliary bench member designated generally by the numeral 2. The main bench member comprises a pair of side rails 3 connected by the cross rods 4. The auxiliary bench 55 member comprises a pair of side rails 5 connected by the cross rods 6.

The main bench member is provided with pairs of legs 7 connected by the cross rods 8 and pivotally mounted on the side rails by means of the pivot arms 9 which are rigidly secured to the outer sides of the legs to overlap the side rails to which they are connected by the pivots 10. A pair of legs 7 is mounted on the outer ends of the auxiliary member side rails to collapse on the under sides 65 thereof.

The side rails of the main bench member have a series of vertical bores 11 therein adapted to receive the removable pin 12 which is pivoted at 13 to a plate on the upper 70 side of one of the side rails of the auxiliary bench member and is adapted to be selectively engaged in the holes 11. A plate terminating in the downwardly engaging projecting hook 14 is mounted on the other 75 auxiliary member side rail by suitable rivets. The hook is adapted to be engaged over the side rail of the main bench member against which the ends of the auxiliary member abut, thereby supporting the auxiliary bench 80 member at right angles to the main bench member.

The position of the auxiliary bench member may be varied to support the tubs in proper relation to the washing machine and wringer, or otherwise, as may be desired. When desired the bench may be collapsed as shown in Fig. II, the auxiliary bench member being swung over and into parallel relation to the main bench member and inverted thereon with the legs in collapsed position, the legs of the main bench member being collapsed against the under side thereof, see Fig. II. The auxiliary bench member when swung to erected position is securely supported and at the same time may be readily adjusted as desired, or collapsed 90 for storage or handling.

Having thus described my invention what I claim as new and desire to secure by 100 Letters Patent is:

1. In a wash bench, the combination of a main bench member comprising connected side rails, one of said side rails having a vertical bore therein, an auxiliary bench member comprising connected side rails, a plate with a projecting downwardly engaging hook support mounted on the end of one of the auxiliary member side rails to engage over a side rail of the main member, and a 105 projecting plate with a pin pivotally mounted on the other auxiliary member side rail 110

to engage said bore in said main member side rail whereby said auxiliary member may be supported at the side of the main member or swung over and collapsed in inverted position upon said main member.

2. In a wash bench, the combination of a main bench member comprising connected side rails, one of said side rails having a vertical bore therein, an auxiliary bench member comprising connected side rails, a plate with a projecting downwardly engag-

ing hook support mounted on the end of one of the auxiliary member side rails to engage over a side rail of the main member, and a projecting plate with a pin mounted on the other auxiliary member side rail to engage said bore in said main member side rail whereby said auxiliary member may be supported at the side of the main member.

In witness whereof I have hereunto set my hand.

JOHN J. BROWN.
